METHOD AND APPARATUS FOR GRINDING

Lawrence J. Cooney, Pittsburgh, Pa., assignor to
 Keystone Grinder & Manufacturing Company,
 Pittsburgh, Pa., a corporation of Pennsylvania

Application February 26, 1935, Serial No. 8,265

1 Claim. (Cl. 51—178)

My invention relates to grinding and, in particular, to the provision of a smooth surface upon articles such as railroad rails, which are subject to severe wear resulting in the formation of defects on the wearing surface.

It has been the practice heretofore to treat defects in railroad rails, chiefly adjacent the ends thereof, with a grinding wheel and, in advanced cases of spalling or chipping, to fill in the defective spots by welding and then smooth the surface with a grinding wheel. Joints between adjacent lengths of new rail have also been leveled off where necessary, due to manufacturing tolerances, by a grinding wheel. This practice is characterized by several objections. In the first place, a grinding wheel can have contact with the rail surface only over a very small area. It is difficult, furthermore, to manipulate the wheel along the rail so as to prevent the formation of an objectionable depression when grinding out defects or leveling joints. In this operation, it is desirable to grind the rail surface on long, gradual slopes in either direction from the defect or high spot being treated and this result is very difficult to achieve with a grinding wheel. Where welding has been resorted to, furthermore, the finished surface of the weld must be precisely in line with the surface of the rail on either side thereof. At joints between rails, the same necessity for exact alignment exists. In cases of these kinds, wheel grinders have been only partially successful in removing surface defects without creating other depressions in the rail surface which are as undesirable as the defects attempted to be removed.

I have invented a method and apparatus for grinding which successfully overcomes the objections to the procedure previously followed, in that it insures that defective or high spots in the wearing surface of rails can be ground out without introducing a steep depression. On the contrary, it is effective to replace the surface defects or high ends with long, gradual slopes which preclude the dangerous pounding action occurring when a heavy train passes over a depression in the surface of the rail at a high speed. The shock on the rail is thus materially decreased and its life considerably lengthened. My invention, furthermore, is capable of grinding the rail head to the proper radius. This has been impossible with the wheel grinders used heretofore, insofar as I am aware.

In accordance with my invention, I provide a wheeled frame adapted to roll on the rail to be treated. A carriage slidably transversely of the

frame carries a source of motive power and a pair of pulleys over which a flexible abrasive belt is trained. The power source has driving connections with one of the pulleys. A back-up plate or presser foot is adjustably supported above the lower run of the belt and, when the belt has been shifted to a position in vertical alignment with the rail head, serves to force the belt into grinding engagement with the rail. Further details of the invention will become apparent as the following description proceeds.

The accompanying drawings illustrate a present preferred embodiment of the apparatus of my invention, from which the improved method will be apparent. In the drawings:

Figure 1 is a plan view of the grinder;

Figure 2 is a side elevation thereof;

Figure 3 is a partial side elevation to enlarged scale;

Figure 4 is a partial sectional view along the line IV—IV of Figure 3;

Figure 5 is a partial side elevation to enlarged scale looking toward the side opposite that from which Figure 3 is taken;

Figure 6 is an elevation of a detail;

Figure 7 is a sectional view along the line VII—VII of Figure 1; and

Figure 8 is a partial plan view, largely diagrammatic, showing a modification.

Referring now in detail to the drawings, the apparatus of my invention comprises a frame 10 which may conveniently be constituted by channel members welded or otherwise secured together. Corner brackets 11 have handle supports 12 extending upwardly therefrom whereby the frame may be manually lifted. The frame 10 is supported on wheeled axles 13, the wheels 13' of which rest on track rails 14. The axles 13 are in two portions, to one of which, 13a, the frame 10 is permanently journaled. The other portions 13b, of the axles are detachably secured to the portions 13a by means of pin and socket joints 16 and set screws 17. Handles 18 in the axle portions 13b facilitate the removal of the latter from the portions 13a when the set screws 17 have been released. The purpose of the divided axles is to permit the machine to be disposed in a small space.

The inner side member of the frame 10 is provided with a jack 19 shown in detail in Figure 5 for raising the shaft portions 13b and the wheels carried thereby when they are to be removed. The jack consists simply of a vertical strut carried in a guide 19a and having rack teeth formed thereon for cooperation with a pinion 55

20 journaled in the frame side member. A handle 21 keyed to the pinion shaft is provided for manual operation of the jack 19. The jack is normally held in elevated position by a holding pin 22.

5 A carriage 23, which may conveniently be constructed of angle bars 24 and cross members 25, has a base plate 26 thereon for mounting a motor 27. While I have shown a motor of the internal combustion type, it will be understood that any suitable type of motor may be employed instead. Cross shafts 28 and 29 are journaled in bearings carried on the side members 24 of the frame 23. The bearings for the shaft 29 are mounted on a plate 29a slidable along the side members 24. The plate is urged to the left by back-up springs 31 and is yieldingly held on the carriage by springs 32. The shafts 28 and 29 are provided with pulleys 34 about which an abrasive belt 35 is trained. The springs 31 obviously constitute a tightening means for the belt 35. The shaft 28 is driven by the motor 27 through a simple pulley and belt drive. The pulleys 28 and 29 and the belt 35 are enclosed in a protective housing, not shown.

10 30 A lever 35a is pivoted on a cross piece attached to the carriage and is linked to the plate 29a. By shifting the lever, the plate 29a can be moved to the right, compressing the springs 31, to facilitate belt changing. The yielding support for the pulley 34 provided by the plate 29a and springs 31 decreases the chance of belt breakage due to whipping, etc. A latch may be provided 15 to hold the plate in retracted position while changing belts.

40 45 The carriage 23 is supported on the axles 13 by rollers 36 and may be shifted laterally of the track rail to permit the pulleys 34 and the belt 35 to be vertically aligned with the rail. A rock shaft 37 journaled in suitable bearings on the outer side frame member has a crank 38 and a hand lever 39 secured thereto. Links 40 are pivoted to the crank and hand lever and to the carriage 23 adjacent its ends. Shifting of the lever 39 thus causes parallel movement of the carriage 23 relative to the frame 10.

50 55 The outer side member of the frame 10 also carries a bracket 41, as best shown in Figures 3 and 4. The bracket has a guide 42 for a vertically movable slide 43. Movement of the slide is controlled by a hand lever 44 pivoted to the bracket 41 and to the slide. The slide is normally held in raised position by a retractible holding pin 43a in the guide 42. The lower end of the slide 43 is formed into a yoke 45. A back-up plate or presser foot 46 is pivotally mounted in the yoke 45 on pins 47. The back-up plate thus extends parallel to the track rail and is rotatable about an axis parallel to the rail. A handle 48 carried by the plate 46 enables the operator to tilt the latter to the desired angle.

60 65 The back-up plate is provided with a strip 49 secured to its ends and extending about the lower surface thereof. An adjusting screw 50 threaded through the plate engages the strip 49 to adjust it relative to the plate. The possible range of adjustment is indicated by the dotted line showing of the strip in Figure 3.

70 75 Pulleys 46a are journaled at the upper end of the bracket 43 and the ends of the back-up plate 46. An idler belt 46b is trained around the pulleys and under the plate, to reduce friction between the latter and the abrasive belt 35. The belt 46b may be of metal and the friction

between it and the back-up plate may be reduced by lubrication.

As shown in Figure 4, the lower surface of the plate 46 is curved to conform to the curvature of the rail head. Longitudinal curvature 5 is provided by the adjustable strip 49.

10 While the method of my invention will probably be apparent from the foregoing description of the machine, a brief explanation thereof will now be given.

15 After the wheeled frame has been placed on the track, it is rolled therealong by hand until it is substantially centered over a defect in the rail which it is desired to remove. The carriage 23 is normally moved inwardly of the frame 10 to provide a clear view of the rail head. Assuming that the motor 27 is running, the carriage 24 is advanced into vertical alignment with the rail by the lever 39. As shown in Figure 3, there is ample clearance between the plate 46 and the rail head to permit the belt 39 to be moved across the rail without actually engaging it. Lowering of the lever 44 will cause the back-up plate 46 to press the belt 35 against the rail head and grind the surface thereof. Tilting of 25 the plate 46 by the lever 48 enables the desired contour of the rail head to be maintained. The adjustable strip 49 on the plate 46 permits a relatively deep defect in the rail to be ground out without introducing abrupt depressions in 30 the surface of the rail. The belt 35, of course, assumes the contour of the strip 49 and when the latter is adjusted to the position shown in dotted lines in Figure 3, it will be seen that the rail head will be ground on gradual, longitudinal 35 slopes. This method of grinding out defects avoids introducing depressions in the rail head which would lead to excessive pounding or battering in subsequent use of the rail.

40 The apparatus may be used to level off the abutting ends of new rails at the joints; to smooth up rail heads after filler metal has been welded thereto; as well as to remove such defects as are susceptible of treatment without welding in filler metal. The extended plane surface of the belt 45 which is forced into engagement with the rail head by the plate 46 makes it possible to align rail ends perfectly at joints, as well as to smooth out defects by grinding into the rail head on gradually sloping lines. The levers 44 and 48 provide a 50 highly flexible control for the grinding operation, the former serving to vary the pressure of the abrasive belt on the work and the latter to cause the belt to follow the transverse curvature of the rail head. Slight lateral movement of the carriage 23 preferably accompanies tilting of the plate 46 by the lever 48 to insure perfect finishing of the rail head in conformance with the conventional contour. When a stretch of one rail of the track has been treated, the machine may be 60 reversed and the other track similarly treated.

65 If it should become necessary to dispose of the machine in a relatively limited space, for example, between a pair of tracks on a long, narrow cut, such as exist on certain railroads traversing mountainous country, it is only necessary to retract the pin 22 and turn the handle 21 so that the jack 18 lifts up the axle sections 13b. Backing off the set screws 17 permits these sections to be removed entirely, whereupon the remainder 70 of the apparatus may be lifted by two men and disposed between the tracks or in any other desired location.

75 The cutting action of the belt may be varied by choosing the proper type of abrasive for the sur-

face thereof and coordinating the speed of the motor 27 therewith. I find that a belt speed of approximately 4500 ft. per minute is satisfactory, with a relatively coarse abrasive surface for the belt. With this combination, the grinding operation is relatively rapid.

In leveling the abutting ends of new rail at the joints, I find it desirable that the abrasive belt move from the higher rail toward the lower. As the high rail may be on either side of the joint, I provide means for reversing the drive for the pulleys 34. Referring to Figure 8, a jack shaft 60 is journaled between the bars 24 and parallel thereto, in suitable bearings carried on cross pieces 61. The shaft 60 carries a reversing gear 62 which may be of any desired known type, having a shifting lever 63. The shaft 60 drives the shafts 28 and 29 carrying the pulleys 34, through bevel gears 64. The shaft of the engine 27 is effective to drive the shaft 60 in either direction, depending on the position of the reversing gear 62.

It will be apparent from the foregoing description that the invention provides a greatly improved method and means for surfacing rails, although it will be understood that this is not the only application of the invention, but it is the principal one I now contemplate. The speed and certainty of operation of the invention are distinctly superior to wheel grinders such as previously employed for this purpose and the finished job is much better than can be obtained with

grinders of the old type. At the same time, the invention can be utilized by relatively unskilled operators and the apparatus is simple and comparatively inexpensive. It is also light in weight so as to be capable of easy manual operation. 5 The movable carriage permits the operator to shift the belt away from the rail at intervals to observe the progress of the grinding operation and thus avoid taking an unnecessarily deep cut. The angular adjustability of the cutting surface 10 to follow the contour of the rail head has already been mentioned, as well as the fact that the grinding surface may be made exactly horizontal or provided with a gradual dip or bow.

Although I have illustrated and described herein but one preferred embodiment and practice of the invention, it will be apparent that many changes in the structure and operation described herein may be made without departing from the spirit of the invention or the scope of the appended claim. 15

I claim:

Rail grinding apparatus comprising a frame adapted to roll on a rail, pulleys supported thereon, an abrasive belt trained about said pulleys for 25 engagement with the rail, and means for pressing the belt against the rail, said means being mounted for movement to and from the rail and for tilting movement about an axis parallel to the rail. 30

LAWRENCE J. COONEY.
